Specification for Design.

Patented Jan. 7, 1919.

Application filed October 21, 1918. Serial No. 259,138. Term of patent 7 years.

To all whom it may concern:

Be it known that I, LEO F. McNALLY, a citizen of the United States, and a resident of New York, borough of Brooklyn, in the county of Kings and State of New York, have invented a certain new, original, and ornamental Design for Locks for Trap-Doors of Vestibule Railway-Cars, of which the following is a specification.

In the accompanying drawing:

Figure 1 is a view showing my improved lock for a trap door of a vestibule railway car in side elevation;

Fig. 2 is a view showing the same in end elevation, and as seen from a position to the right of Figs. 1 and 3;

Copies of this patent may be obtained for five cents each, by addressing the "Commissioner of Patents, Washington, D. C."

Fig. 3 is a view showing my invention in plan, and;

Fig. 4 is a view showing my invention in end elevation, and as seen from a position to the left of Figs. 1 and 3.

I claim as my invention:

The ornamental design for a lock for the trap door of a vestibule railway car, substantially as herein illustrated.

LEO F. McNALLY.
